UNITED STATES PATENT OFFICE.

GEORGE W. CAMPBELL, OF COLUMBUS, OHIO.

MORTISING-MACHINE.

1,245,677.

Specification of Letters Patent.

Patented Nov. 6, 1917.

Application filed July 23, 1913, Serial No. 780,625. Renewed June 24, 1916. Serial No. 105,730.

To all whom it may concern:

Be it known that I, GEORGE W. CAMPBELL, a citizen of the United States, residing at Columbus, in the county of Franklin and 5 State of Ohio, have invented certain new and useful Improvements in Mortising-Machines, of which the following is a specification.

This invention relates to improvements in 10 mortising machines.

One of the objects of the invention is to provide means for causing the cutting tool to travel at a uniform speed across the mortise.

15 A further object of the invention is to provide means for causing the point of the tool to travel in a straight line parallel with the face of the piece being mortised.

20 A further object of the invention is to provide means for causing the tool to travel uniformly with the operating device.

A further object of the invention is to simplify and cheapen the construction and 25 make more effective the operation of devices of this character.

The invention consists in the constructions and combinations of parts hereinafter described and set forth in the claims.

In the accompanying drawings:

30 Figure 1 is a side view of a machine embodying my improvements, the bit having just completed its travel to the lower end of the mortise.

Fig. 2 is a top plan view of the same.

35 Fig. 3 is a longitudinal section on the line 3—3 of Fig. 1.

Fig. 4 is an end view.

40 Fig. 5 is a vertical section on the line 5—5 of Fig. 1, the bit being in mid position but moving upward.

Fig. 6 is a vertical section on the line 6—6 of Fig. 1.

Fig. 7 is a vertical section on the line 7—7 of Fig. 1.

45 Fig. 8 is a detail of a portion of the shifting mechanism.

Fig. 9 is a detail of a portion of the oscillating mechanism.

50 Like parts are represented by similar characters of reference throughout the several views.

In the said drawings, 1 and 2 represent two rails or ways, connected together at the rear by the handle portion 3 and at the front 55 by a bar 4. The bar 4 is slotted as indicated

at 5 and provided with two pairs of clamps for the purpose of clamping the machine to the door or other article in which the mortise is to be made. The clamps are shown in the nature of thumb-screws 6 (see Figs. 1 and 60 4), screwed into the forwardly extending bosses 4^a and having swiveled fiber washers to engage the sides of the door in a manner common in devices of this character.

Slidably mounted upon the ways 1 and 2 65 is a carrier consisting of side frame pieces 8 and 9, rear connecting piece 10, front connecting bar 11 and intermediate cross bar 12; the side pieces being each provided with a pair of projecting bosses 8^a and 9^a to receive 70 the ways and provide a sliding connection between the parts; the movement of the carrier being limited in one direction by the handle 3 and in the other by the cross bar 4.

Secured in the cross bar 12 is a stud bolt 75 15 (best shown in Fig. 3), the said bolt having a screw-threaded connection with said cross-bar. Journaled on this stud or bolt between the frame part 12 and the head of the bolt is the main driving-wheel 16. The 80 bolt is also provided on the opposite side of the frame part from the driving wheel with an extended reduced stud portion 15^a. A bracket 14, secured to the frame part by screws 14^a, which serve to space it therefrom, has a stud 17 arranged in line with the stud 15^a, said stud 17 being screw-threaded into the bracket to secure it therein. Journaled upon these stud portions 15^a 85 and 17 is the hub of an oscillating sleeve 18 90 within which is journaled the shaft 19 of the cutting tool 20; said tool and shaft being secured together by a screw-threaded connection.

The tool and its shaft are rotated by the 95 main driving wheel through the medium of an internal gear on said wheel; a pinion 22, journaled on the stud 23, supported by the sleeve 18; beveled gear 24 formed integrally with said pinion 22, and a beveled pinion 100 25, splined to the tool shaft so as to permit said shaft to slide therethrough. The sleeve 18 is enlarged or formed with a housing 18^a so as to inclose the pinion 25; said housing being formed with an opening so as to receive the teeth of gear 24.

Tool oscillating devices.

In prior machines of this character it was customary to oscillate the tool by some form 110

of eccentric connection, which caused the tool to travel at varying speeds; that is, the tool at certain points in its oscillation would be moving faster than at other points in its oscillation, or vice versa, depending upon the position of the eccentric with respect to the center of oscillation of the tool. Further, with this old manner of oscillating the tool it was necessary to revolve the driving wheel as many times for a short mortise as for a long one; that is, in cutting a mortise of, say, two inches in length it would be necessary to revolve the driving wheel in oscillating the tool from one end of the mortise to the other as many times as it would be in cutting a mortise six inches in length. To overcome these difficulties and objections I have provided for oscillating the tool by means of a screw in the following manner:

Supported loosely in bearings 26 and 27 on the respective frame parts 8 and 9 is a screw 28, (see Figs. 1, 5 and 6) having connected with the lower end thereon a beveled gear 29; the hub of said gear and a collar 30, holding said gear in position in the bearings. Also supported in a bearing formed in a bracket 31 depending from the frame part 9 is a shaft 32, arranged at right-angles to the screw 28. Secured to one end of the shaft 32 is a gear 33 meshing with external gear teeth 34 on the main driving wheel so that as said wheel is rotated the shaft 32 will also be rotated, slidably mounted upon the shaft 32 but rotatably connected therewith, as by a spline, is a pair of connected pinions 35 and 36 adapted to be shifted at the end of each oscillatory movement of the tool so as to alternately bring said pinions into mesh with the beveled gear 29 to cause the screw 28 to be rotated, first in one direction and then in the other. The screw 28 extends through a screw-threaded nut 37 having a flanged neck 37^a which is pivotally connected with the housing 18^a of the sleeve 18 so that as the screw is revolved it will be seen that the sleeve and tool will be oscillated; the connection between the nut and housing being such as to permit of a limited movement of the parts so as to allow the sleeve 18 to swing in the arc of a circle while the nut travels in a straight line, as shown in Figs. 1, 3, 5, 6 and 9.

In order to shift the pinions 35 and 36 to change the direction of rotation of the screw, I have provided the following mechanism: Slidably mounted in the frame parts 8 and 9 is a bar 38, having thereon two adjustable pins 39 and 40. The lower end of this bar 60 is pivotally connected with an arm 41, which arm is mounted loosely upon the rock-shaft 42, arranged beneath and at right-angles to the shaft 32 and being supported by a bracket 43 extending from the frame portion 9. The free end of the arm 41 has con-

nected thereto a coil spring 44, the opposite end of which is connected to the bracket 43 back of the pivotal point of the arm 41 so that when said arm is thrown past the center in either direction by the movement of the bar 38, the spring will exert its influence thereon for the purpose to be described. Extending laterally from the arm 41 is a pin 45 (see Fig. 8 for detail) which extends into a slot 46 in a collar 47 fast to the rock shaft 42; the said pin normally occupying a central position in said slot. The rock shaft 42 has laterally extending fork arms 48 provided with pins 49 which project into a groove 50 in the hub of the pinions 35 and 36 so that as said shaft is rocked in either direction the pinions will be shifted.

The result of this construction is that as the tool reaches the limit of its oscillation in either direction the end of the sleeve 18 will strike one of the pins 39 or 40 and shift the bar 38, causing the arm 41 to swing past the center, whereupon the spring 44 will exert its influence and give the arm a still further movement. By the time the spring begins to exert its influence the pin 45 will have reached the end of the slot 46 and thereupon the shaft 42 will be rotated to shift the pinions. It will be observed that the arm 41 is allowed a limited movement with respect to the rock-shaft before said shaft is rocked, which is for the purpose of allowing the bar 38 to perform another operation, to be described hereinafter, before this movement ceases by the disengagement of the pinions 35 or 36 with the gear 29 of the screw 28.

This construction also eliminates the necessity of any fine adjustment between the parts as it will be seen that it is only necessary that the bar 38 should throw the spring 44 into action by swinging the arm a short distance, the spring then performing the actual work of shifting the pinions.

By varying the distance between the adjustable pins 39 and 40 it will be seen that the mortise may be cut to any length desired.

Tool feeding devices.

Means are provided for feeding the tool a step forwardly at the end of each oscillatory movement thereof by sliding its carrier along the ways in the following manner: Rotatably mounted in the bar 4 is a rearwardly extending screw 51 which passes through a bracket 8^b on the side frame piece 8, as shown best in Fig. 6. The bracket 8^b carries a follower 52 normally held by a spring 53 in engagement with the threads of said screw 51 so that as the screw is rotated the carrier will be moved forward. The screw is arranged to be given a partial rotation near the end of each oscillatory movement of the tool by spring pawls 54 and 55.

(Fig. 5), connected with the bar 38, acting upon a ratchet 56, splined to the screw and confined between two projecting portions 57 on the bar 38 so that said ratchet wheel will 5 move along the screw with said carrier. One of the pawls is arranged on one side of the ratchet wheel and the other pawl on the other side thereof, said pawls being extended in opposite directions so that the movement 10 of the bar in either direction will move the ratchet wheel and hence the screw in the same direction. In moving the carrier back to its starting position, the spring-pressed follower will be withdrawn through the medium 15 of the finger piece 52^a to permit the carrier to readily slide back on the ways. The parts are so timed that the bar 38 will have moved the screw 51 before the rotation of the screw 28 has ceased by the disengagement 20 of the pinions 35 or 36 previously described.

Device for causing tool to oscillate in straight line.

25 In prior machines of this character, the tool, in oscillating, has traveled in the arc of a circle, thereby causing the inner wall of the mortise to be formed on the arc of a circle. In order that this inner wall may 30 be formed on a straight line I have provided for causing the tool, in oscillating, to travel in a straight line in the following manner: As shown in Fig. 3, the rear end of the tool shaft 19 is extended through the hub of the 35 sleeve 18 into a sleeve 58. A cotter pin 59, extending through the walls of the sleeve 58 and through a circumferential groove in the shaft, allows said shaft to rotate in said sleeve but confines it against longitudinal 40 movement therein. The sleeve 58 is formed with a transverse slot, 60, as shown best in Figs. 1 and 3. This slot 60 receives the rear connecting bar 10 which is provided with a curved central portion 10^a. The sleeve 58 45 is bored to a depth shown in Fig. 3 so that balls or rollers 61 and 62 may be inserted between the end of the shaft 19 and the end of the bore, one on either side of the arc 10^a to eliminate friction. The curved central 50 portion of the frame is so formed that as the tool oscillates it will be gradually withdrawn and projected through the sleeve 18 so as to maintain its outer cutting edge upon a straight line across the mortise.

55 Having thus described my invention, I claim:

1. In a mortising machine, an oscillatory tool, a screw having an operative connection with said tool, and means for reversing the direction of rotation of said screw on either side of the center of oscillation of said tool.
2. In a mortising machine, an oscillatory tool, a screw having an operative connection with said tool, means for rotating said screw consisting in part of a pair of shiftable

pinions, a rock-shaft having a shiftable connection with said pinions, an arm loosely mounted on said rock-shaft arranged to rock the same in either direction but capable of a limited movement relatively thereto, a 70 normally inoperative spring connected with said arm, means for throwing said spring into operative position at points on either side of the center of oscillation of said tool, and devices operated by said last-mentioned 75 means for producing a forward feed of said tool during the limited movement of said arm relatively to said rock-shaft.

3. In a mortising machine, an oscillatory tool, a screw having an operative connection 80 with said tool, means for rotating said screw consisting in part of a pair of shiftable pinions, a rock-shaft having a shiftable connection with said pinions, an arm loosely mounted on said rock-shaft and arranged 85 to rock same in either direction but capable of a limited movement relatively thereto, a spring connected with the free end of said arm, a slidable bar pivotally connected with said arm, adjustable pins on said bar arranged in the path of said tool on either side of the center of oscillation thereof so that said spring will be thrown into operative position to shift said pinions, and devices operated by said bar during the limited 90 movement of said arm relatively to said rock-shaft for producing a forward feed of said tool.

4. In a mortising machine, an oscillatory tool carrier, a tool rotatably mounted in 100 said carrier together with means for rotating said tool, a screw, a swiveled connection between said carrier and said screw, and means for operating said screw for the purpose of oscillating said carrier and tool. 105

5. In a mortising machine, an oscillatory sleeve, a cutting tool, a shaft slidably mounted in said sleeve, means for oscillating said parts, a second sleeve with which said shaft is rotatably connected, a grooveway in said 110 last mentioned sleeve, and a curved non-oscillatory part located in said groove to cause said shaft to be moved longitudinally through said first mentioned sleeve during the oscillatory movement of the parts, for 115 the purpose specified.

6. A mortising machine comprising a framework, a bit, means for rotating said bit, means for oscillating said bit during the rotation, and means for varying the 120 length of such oscillation, said last means being such that the number of oscillations is increased correspondingly with each reduction in length of oscillation and vice-versa.

7. A mortising machine comprising a framework, a bit, means for rotating said bit, means for oscillating said bit during its rotation, means for varying the length 125 of the oscillations, and means for maintain- 130

ing a uniform rate of oscillatory movement of said bit for all lengths of oscillatory movement.

8. A mortising machine comprising a framework, a carriage slidable on said framework, a bit, a bit supporting structure pivotally mounted on said carriage, a rotatable cross feed screw for said bit supporting structure, means for imparting rotation to 10 said bit, said bit supporting structure having

a part slidable toward and from the pivot thereof and having threaded connection with said cross feed screw.

In testimony whereof, I have hereunto set my hand this 5th day of July, 1913.

GEORGE W. CAMPBELL.
